APPARATUS FOR PRODUCING
PHOTOGRAPHS

Garnet Peter Grant, Jr., Plandome, N. Y., assignor to Grant Photo Corporation, New York, N. Y.

Application March 5, 1937, Serial No. 129,165

13 Claims. (Cl. 95—14)

This invention relates to the production of photographs.

In commercial photography there is a practice of making several small pictures of a person in different poses on a strip of sensitized paper and selling the pictures to the person who is the subject of the photograph. In order to be practical it is necessary to develop the pictures immediately after the exposures have been made so that the person whose picture is taken may purchase the same. The apparatus of the present invention is particularly adapted for such work but may be used in other fields of photography.

In the past, where mechanical means have been provided to handle the film or sensitized paper through the various stages of development, there have been several disadvantages. In particular, the film or sensitized paper is brought into contact with the surface of a roller or other handling mechanism while the film is in the developing solution. This contact or friction on the emulsion of the film causes a faster development in the area of contact with the roller or other mechanism. This results in an unequal development of the picture. Accordingly, an object of the present invention is to provide means for mechanically handling a film or sensitized paper without having the emulsion on the film come in contact with any mechanism.

One object of the present invention is to provide an apparatus including a camera and a developing mechanism with which a large number of pictures may be rapidly produced and in which a large number of pictures may be produced simultaneously in a continuous cycle. Various machines have been developed in the past for producing one or more small pictures on a strip of film or paper, but each of these prior machines has had certain distinct disadvantages. The general object of the present invention is to provide an apparatus which will be rapid, efficient, and which will overcome the disadvantages of the prior art.

In the past machines have been used in which the operation was substantially entirely automatic. When a breakdown occurred in any part of the mechanism the entire apparatus was rendered useless. One of the principal objects of the present invention is to provide an apparatus which is semi-automatic, and in which the various parts of the mechanism will co-operate to automatically develop a picture, but in which the various parts are independent so that in the event of a breakdown of one part the rest of the mechanism may be used. Specifically, one ob-

ject of the invention is to provide an automatic developer which will mechanically receive pictures from a camera and develop the same, but so constructed that in the event of a breakdown the mechanical and automatic features may be readily eliminated and the apparatus operated by hand.

A further object of the invention is to provide a film receiving device which will receive the film from a camera and support the film during the successive stages of development. Another object is to provide mechanical means to deliver the film holding device to the developer, and automatic means to start the film through the developer in proper timing with the rest of the mechanism. A further object is to provide a single operating mechanism to control the various operations in connection with the developer to insure proper timing of the various mechanical movements.

A further object of the invention is to provide an automatic developing apparatus in which the film will be immersed and then removed from the developing chemicals in a step-by-step process through the several phases of development and finally delivered as a finished picture to the outside of the machine. A further object of the invention is to provide means to control the temperature of the developing chemicals and the time for development. A further object of the invention is to provide a booth or enclosure for the entire apparatus with controls on the outside of the booth, such booth being so constructed that in the event of an emergency the operator may enter the booth and carry on the development of the pictures by hand.

The invention consists of the construction, combination and arrangement of parts, as herein illustrated, described and claimed.

In the accompanying drawings, forming part hereof, is illustrated one form of the invention, in which drawings similar reference characters designate corresponding parts, and in which:

Figure 1 is a side elevation of the entire apparatus, with the booth or housing broken away;

Figure 2 is a plan view of the mechanism shown in Figure 1, with the booth broken away;

Figure 3 is an enlarged detail in side elevation showing the camera operating means and the devices to receive the strips of exposed film;

Figure 4 is an enlarged fragmentary detail in rear elevation showing the shutter release operating means;

Figure 5 is a fragmentary detail in vertical section, taken approximately on line 5—5 of

Figure 3, looking in the direction indicated by the arrows, and showing the film cut-off means;

5 Figure 6 is a detail in vertical section, taken approximately on line 6—6 of Figure 2, looking in the direction indicated by the arrows, and showing the transfer of the film to the developer;

10 Figure 7 is an enlarged fragmentary detail in vertical section, taken approximately on line 7—7 of Figure 2, looking in the direction indicated by the arrows, showing the main operating cam in side elevation and a portion of the developing tanks in section;

15 Figure 8 is a vertical section taken approximately on line 8—8 of Figure 1, looking in the direction indicated by the arrows, showing the operating means in front elevation;

20 Figure 9 is a vertical section, partly in side elevation and partly broken away, taken approximately on line 9—9 of Figure 2, looking in the direction indicated by the arrows;

25 Figure 10 is a fragmentary detail in horizontal section, taken approximately on line 10—10 of Figure 9, looking downward, showing the film delivery locking mechanism; and,

30 Figure 11 is a perspective showing the booth which encloses the apparatus and the operating controls on the outside thereof.

The camera operation

35 Referring to the drawings, and particularly to Figures 1, 2, 3, and 11, a booth 12 is provided of ordinary structure. The booth 12 is light-proof and a camera 13 is so arranged therein that a subject on the outside of the booth may be photographed. One portion of the booth is arranged to receive the subject to be photographed and is provided with the usual lights 14 which are concealed behind frosted glass 15 to effect a proper diffusion of light. The subject to be photographed is seated on an adjustable stool 16 so as to be in proper alignment with the camera 13.

40 The camera illustrated is adapted to use direct positive paper instead of the ordinary film, so that the film may be developed as the final picture. 45 A reflecting prism 17 is provided rearwardly of the lens in the camera 13 to effect a reversal of the image so that the resultant picture will be a true photograph. An ordinary flexible shutter release cable 18 is provided and is held in position 50 on the camera 13. In the camera 13 is disposed a roll 19 on which is carried a continuous film 20. As best shown in Figure 3, the film 20 is fed upward between film feeding rolls 21 and thence under the reflecting prism 17 to be exposed.

55 A handle 22 is provided on the outside of the booth 12 and rocks a shaft 23 to which are connected short and long complementary links 24. The longer link 24 is pivoted to a rockable plate 25 which in turn rocks on the axis of one of the feed rolls 21. The plate 25 is formed with an extension 26 which carries the shutter release means best shown in Figure 4. The shutter release means comprises a U-shaped member 27 held in slidable relation to an extension 26 by rivets 28 which are movable in slots 29 in the member 27. A pin 30 is carried by the extension 26 and has connected thereto a spring 31, the opposite end of which is connected to the lower portion of the member 27. When the handle 22 is 70 turned the links 24 cause the plate 25 to rotate. The upper portion of the member 27 will strike the head of the shutter release 18 and an exposure will be made. Since the extension 26 of the plate 25 moves further than the movement 75 necessary to operate the trip 18, the member 27

will come to rest after moving the trip 18 upwardly, and the extension 26 will continue until the rivets 28 have reached the limits of the slots 29. When the plate 25 is retracted the spring 31 will return the member 27 to its normal position. 5 The retraction of the plate 25 will be accomplished by spring action on the plate 25 or the links 24 or the shaft 23, or the retraction may be by manual movement of the lever 22.

Adjacent the plate 25 is a ratchet 32 carried 10 by the larger feed roll 21. Separated from and operated by the plate 25 is a pawl 33. As the handle 22 is operated to make an exposure the pawl 33 will travel on the ratchet 32. When the plate 25 is retracted the pawl 33 will move the ratchet 32 and will cause an unexposed portion or section of film 20 to be moved by the feed rolls 21 under the prism 17 and the parts are ready for another exposure. A spring-pressed dog 34 is provided to prevent movement of the ratchet 32 20 in a reverse direction.

Carried by the shorter link 24 is a plate 35 to which is pivoted a spring controlled pawl 36. 25 Adjacent the pawl 36 is disposed a ratchet 37 provided with projecting pins 38 and having a spring controlled dog 39 to prevent improper movement of the ratchet 37. As an exposure is made, as above described, the pawl 36 will engage the ratchet 37 and move the same one step. As the ratchet 37 rotates, one of the pins 38 will ride 30 against a lever 40 which is pivoted at 41. When four exposures have been made the pin 38 will ride past the end of the lever 40 permitting it to rock on its pivot 41, and a spring pressed clapper 42 will strike a bell 43 to signal to the operator of 35 the camera that four exposures have been made. The teeth on the ratchet 37 may be so arranged that any desired number of exposures can be made before the bell 43 is struck.

When the desired exposures have been made the 40 exposed film is cut from the roll and is ready to be developed. An operating handle 44 (Figure 11) is provided to cut the film and is connected to a rockable shaft 45. Operated by the shaft 45 is a short link 46 to which is pivoted a longer 45 link 47 which in turn is connected to a rockable cam 48 which is pivoted at 49. A knife 50 is provided to cut the film 20 and is best shown in Figure 5. The knife 50 is pivoted at 51 and formed with an extension 52 abutting the edge of the 50 cam 48 so that upon movement of the cam 48 the knife 50 is rocked to the dotted line position shown in Figure 5 to cut the film 20 as it passes through a slot 53 in the rear of the camera 13. A spring 54 is provided to return the knife 50 to its 55 normal position and the film 20 passes over the edge of a support 55 past which the edge of the knife 50 operates to cut the film.

Delivery of film to developer

60 As the film 20 leaves the camera 13 through the slot 53 the film is received in a carrying frame designated generally as 56. The film frame 56 comprises a transverse supporting member 57 to which is connected complementary arms 58 having their upper ends 59 bent around the supporting member 57. On the opposite ends of the arms 58 are disposed complementary channel members 60 to receive the strip of film 20. The channel members 60 are perforated by openings 61 to permit drainage of developing chemicals as herein-after described.

65 Adjacent to and supported by the base of the camera 13 is a rack 62 formed in any suitable manner and having its outer end supported by a 70

brace 63 connected to the base of the camera 12. A number of the film frames 56 are disposed in a flat position in the rack 62, the channel members 66 of the lowermost frame 56 being in alignment 5 with the slot 63 to receive the film 28 as it is moved after exposure. If desired, the rack 62 may be removable so that a number of frames 56 can be loaded thereon and the rack 62 set in position.

10 When a section of exposed film 28 has been moved onto the frame 56 and cut from the roll, the lowermost frame 56 is ejected from the rack 62. The ejection is operated by the cam 48 which operates a link 64. The link 64 is formed 15 with a slot 65 in which is movable a pin 66 carried by the cam 48. The link 64 is best shown in Figure 3 and in the position there shown the cam 48 has been partially turned so as to operate the knife 58 but not move the link 64. Normally, the 20 pin 66 rests in the left-hand end of the slot 65 in the link 64. As the cam 48 is turned the knife 58 is operated and then the pin 66 engages the right-hand end of the slot 65 and moves the link 64 toward the right-hand of Figure 3.

25 An offset bellcrank lever 67 is connected to the link 64 at 68 and operates on a pivot 69. The opposite end of the bellcrank 67 is formed with a slot 70 through which is disposed a pin 71 connecting with an extension 72 on an ejector plate 30 73 which operates in a guideway 74 so that the ejector plate 73 abuts the bottom of the film frame 56 in the rack 62. As the parts are moved the lowermost frame 56 in the rack 62 is ejected and the plate 73 supports the remaining frames 35 56 until the plate is retracted and the stack of frames 56 permitted to drop down so as to present another frame 56 in position to receive a section of film 28. When the parts are operated they may be returned to normal position by hand operation of the lever 44 or the return may be effected 40 by any appropriate spring action.

When the frames 56 are ejected from the rack 62 they are received on a table 75 which is provided with extensions 76 underlying the stack of frames 56, each extension 76 being provided with a lip 77 to prevent a frame 56 from falling out of the mechanism. As a frame 56 is delivered to the table 75 it is in a horizontal position and when free of the rack 62 falls to a vertical position. In Figure 6 the lowermost frame 56 is shown at the beginning of an ejection and the dotted line position indicates the path of movement taken by the frame 56 until it hangs in a vertical position, being supported by the ends of the cross-member 57 overlaying the edges of the table 75. The table 75 is provided with a central opening bounded by curved walls 78 which are spaced from one another by the width of a frame 56 so that the frame may be slid along the table 75 in an arc to be positioned for delivery to the developer.

In order to transfer the frame 56 from a point adjacent the ejector to a point adjacent the developer, there is provided an operating handle 79 on the outside of the booth 12 to which is connected a shaft 80. Operated by the shaft 80 are a pair of complementary bevel gears 81, the secondary of which is affixed on a rotatable post 82 secured in suitable supports 83. Carried by the 70 post 82 is a horizontal rod 84 extending across the opening in the table 75, the outer end of which is provided with a wheel 85 so that the rod 84 may freely turn with the post 82 as a pivot. Carried by the rod 84 is a gate 86 which is freely rotatable in one direction on the rod 84 but which

is prevented from movement in the opposite direction by means of stop pins 87 carried by the rod 84.

When the frame 56 comes to rest in a vertical position after being ejected from the rack 62 it will normally have passed freely through the gate 86. If it has not passed through the gate 86 the rod 84 may be retracted slightly and the gate 86 will rise, pass over the frame 56 and fall therebehind. Upon forward movement of the rod 84 10 by operation of the handle 79 the frame 56 will be slid along the table 75 in an arc until it has traveled approximately 90° and is ready for delivery to the developer.

Since the frames 56 must be actually inserted 15 in the developer in time with the automatic operation of the developer as hereinafter described, an independent mechanism is provided to insert the frames 56 onto the trackway of the developer. The delivery effected by the mechanical operation 20 of the gate 86 could be made automatic and synchronized with the automatic operation of the developer, but in the present embodiment of the invention as disclosed herein, the two mechanisms are maintained separate. Near the right- 25 hand end of the table 75 is disposed a delivery lever 88 which is pivoted at 89 to the table 75 and is adapted to operate under the table 75 with the outer end of the lever 88 passing through the path of movement of a frame 56 and contacting 30 the top portion 59 of the frame 56 for the purpose of pushing the same onto the trackway of the developer hereinafter described.

The lever 88 is connected to a link 90 on the top of the table 75 which link 90 is in turn connected to a plate 91 pivoted at 92 to the table 75. The plate 91 has connected thereto a link 93 which in turn is connected to a second plate 94 which is pivoted at 95 and operates a further link 96. The link 96 crosses the ejector mechanism 40 and accordingly is provided with an arched portion 97, as best shown in Figure 9, to permit the passage of the frame 56 thereunder. The end of the link 96 is formed as a U-shape 98 and is connected with a lever 99 which is pivoted at 100 and 45 which is adapted to operate simultaneously with the lever 88. The levers 88 and 99 together co-operate to force a frame 56 onto the trackway of the developer hereinafter described. In the position shown in Figure 2 the levers 88 and 99 50 have just delivered a frame 56 to the developer and upon retraction the ends of the two levers will be out of the line of movement of a frame 56, so that a frame 56 may be delivered by the gate 86 to a point between the levers 88 and 99 and the 55 developer.

The operation of the levers 88 and 99 is automatic and is synchronized with the operation of the developer. It is essential that no frames 56 be delivered by the rod 84 and gate 86 during 60 the moments when the levers 88 and 99 are in the operative position shown in Figure 2, because the projecting ends of the levers upon retraction would move the frame 56 in an improper direction toward the ejector mechanism. Accordingly, a control means is provided which is best shown in Figure 10. A detent 101 is formed in the rotatable post 82 into which detent moves a spring controlled latch 102, which is carried on a pivot 103 above the lever 99. The lever 99 70 is provided with a pin 104 which operates through a slot and contacts the latch 102. When the lever 99 is in the retracted position shown in the left-hand dotted lines of Figure 10, the pin 104 moves the latch 102 from the detent 101 to the 75

dotted line position, and the post 82 is free to rotate. As the lever 88 moves to the operative position shown in full lines, the latch 82 engages in the detent 101 and locks the post 82.

5 The operation of the levers 88 and 98 is controlled by the movement of the rockable plate 91. The plate 91 is moved by a mechanism controlled and operated by the automatic mechanism of the developer. It is believed a clearer understanding 10 of the operation may be obtained by first describing the developer and the operation thereof.

The developer

As best shown in Figure 1, a table or support 15 105 is provided on which is disposed a large tank 106. The tank 106 is provided with a drain pipe 107 to which may be removably connected an 20 overflow pipe 108 to maintain a desired water level in the tank 106. Longitudinally of the tank 106 are disposed spacers 109 upon which are set a number of small tanks 110 to contain the various chemicals used in the several steps of developing a picture. A number of water tanks 111 are provided and one tank 111 is disposed adjacent to each tank 110. A water supply pipe 112 is controlled by an ordinary valve 113. The pipe 112 is formed with several branches which terminate in outlets 114, at the ends of the several water tanks 111. The opposite wall of each tank 111 is formed with a recess 115 to permit the overflow of water into the main tank 106.

With this arrangement a constant flow of water may be maintained from the pipe 112 and 35 discharged through the overflow 108 and drain pipe 107. The tank 106 will fill with water to the top of the overflow 108 and will circulate around the several chemical tanks 110. In this way the temperature of the chemicals in the tanks 110 may be controlled. In cold weather 40 where it is not desired to cool the contents of the tanks 110, the overflow 108 may be removed and the water from the tanks 111 will flow directly into the drain 107 without circulating around the tanks 110.

45 Carried by the edge of the tank 106 is a horizontal angle iron frame 116. On one side of the frame 116 is provided a plurality of main vertical supporting posts 117 and on the opposite side of the frame 116 are provided complementary supporting posts 118. All of the mechanism hereinafter described is supported entirely from the frame 116 which is merely set on the edge of the tank 106 and is not secured thereto. In the event of an emergency the entire automatic developing mechanism may be lifted from the tank 106 and the various tanks 110 and 111 50 may be used for hand developing. The frame 116 and the various supports carried by it are secured to the table 75 and its associated parts 60 by bolts and wing nuts 119 which may be readily removed in the event it is desired to separate the developing mechanism from the other mechanisms.

65 Carried by one post 117 is an electric motor 120 which supplies movement to a worm drive 121 of ordinary construction. The worm 121 operates a worm wheel 122. An auxiliary vertical frame member 123 is provided and is maintained rigid 70 by a cross member 124 near its lower end. The member 123 may rest on the table 105.

A transverse shaft 125 has its ends journaled in the supports 117 and 123 and is rotated by the worm wheel 122. Carried by the shaft 125 is a 75 cam 126 having one large extended face 127 and

a plurality of small projections 128. The operation of the cam 126 causes the film frames 56 to be raised and lowered in the tanks 110 and 111, as hereinafter described. On the cam 126 there is a portion on either side of the point 5 marked 129 on Figure 7 where there is no projection 128. This clear portion is provided so that the mechanism controlled by the cam 126 will remain stationary while frames 56 are being fed on by the action of levers 88 and 98, as 10 hereinafter described.

An extension 130 is provided on the post 117 and a lever 131 is pivoted at 132 to the extension 130. The opposite end of the lever 131 is connected to a twisted link 133, the upper end of 15 which is pivoted to the mid-point of a transverse bar 134. The front end 135 of the bar 134 is connected to a longitudinal bar 136 which is rotatable and the ends of which are journaled in the two posts 117. The opposite end of the 20 transverse bar 134 is connected to a U-shaped frame 137 having arms 138 through the center of which passes the bar 136 and to which the arms 138 are connected. A counter-balance 139 is secured to the frame 137 to permit easy movement of the parts, as hereinafter described.

To the end of each arm 138 are connected transverse U-frames 140 by means of pivots 141. The U-frames 140 are provided with depending arms 142 which support a longitudinal trackway 30 143. The trackway 143, as best shown in Figure 8, comprises a pair of relatively wide strip 144, one on either side of a narrow strip 145 so as to leave a space therebetween into which may be received the ends of the supporting member 35 57 of the frames 56.

As the cam 126 is rotated the large face 127 will ride against the lever 131 and depress the same. The lever 131, acting through the link 133 will draw downwardly the transverse bar 134. The bar 134 will carry with it the frame 137, and the arms 138 will be rotated with the bar 136. As the arms 138 rotate the frames 140 will be raised and the trackway 143 will also be raised. As the cam 126 travels further the parts 45 will return to their positions through gravity and the weight of the trackway 143 and frames 140. The counter-balance weight 139 is not sufficient to prevent the lever 131 from bearing against the cam 126 at all times. After the cam face 127 has passed out of contact with the lever 131 the lever will be moved to a small extent by each projection 128 as it passes. This will effect a vertical agitation of the trackway 143 for the purpose hereinafter described.

As the forward end of the arms 138 move upward to raise the trackway 143, the line of motion will be a slight arc. This will have a tendency to cause a slight swinging motion of the trackway 143 since it is suspended solely by the pivots 141. To prevent this, vertical guideways 60 (not shown) may be provided in which the trackway 143 or the arms 142 may operate.

In order to advance the frames 56 along the trackway 143 a horizontal motion is provided. A vertical pitman 146 is pivoted at 147 to a bracket 148 carried by one post 117. On the pitman 146, near its lower end, is formed an extension 149 and the lower end is formed with a reduced portion 150. The pitman 146 has 70 formed therein a longitudinal slot 151 through which is disposed a stud 152 carried by a disc 152 which is operated by the shaft 125.

Extending from each post 117 is a transverse support 154 having its forward end supported 75

to the post 118 by a short angle iron 155. A longitudinal bar 156 has its ends 157 bent around the transverse supports 154. Carried by the supports 154 are blocks 158 on either side of the ends 157 so that the bar 156 is free to slide longitudinally of the apparatus.

A lever 159 is carried on a pivot 160 on one transverse support 154. One end 161 of the lever 159 is bifurcated to receive the reduced end 150 of the pitman 146. The opposite end 162 of the lever 159 is also bifurcated and engages a pin 163 carried on one of the bent ends 157 of the bar 156. Depending from the bar 156 are a plurality of angle members 164 adapted to engage behind the frames 56 to push the same along the trackway 143. The initial angle member 165 is slightly curved, as best shown in Figure 7, so that it may more readily engage a frame 56 if the same is not in proper position.

As the cam 126 rotates, the disc 152 will rotate therewith and the pitman 146 will move back and forth through the action of the stud 163 in the slot 151. As the cam face 127 engages the lever 131 the trackway 143 will be raised to the position shown in Figure 8. At that time the stud 163 will be in the upper part of the slot 151 and further movement will cause the pitman 146 to move to the left from the position shown in Figure 7. This movement will rock the lever 159 and move the bar 156 toward the right. Any frames 56 which are in the trackway 143 will lie in the path of movement of the angle members 164 or the initial angle member 165. Upon movement of the bar 156 the frames 56 will be advanced from a position over one tank 110 to a position over the succeeding tank 111.

As the cam face 127 passes the lever 131 the trackway 143 will again be lowered and the frames 56 immersed in the several tanks. As the cam 126 continues to turn, the pitman 146 will be moved from left to right causing the bar 156 to return toward the left to its normal position.

When the trackway 143 is in the lowered position as shown in Figures 1 and 7, the trackway is in alignment with the upper surface of the table 75 so that any frames 56 which are carried by the table 75 may be readily entered onto the trackway 143 by means of the levers 88 and 89. It is necessary that the levers 88 and 89 operate only when the trackway 143 is in alignment with the table 75 and not in motion. During the time that the plain surface on either side of point 129 on the cam 126 is in contact with the lever 131, there will be no movement of the trackway 143. It is during this interval that the levers 88 and 89 are operated.

A horizontal pitman 166 is connected by a pivot 167 to the extension 149 on the vertical pitman 146. The horizontal pitman 166 is offset at 168 and twisted so that its outer end is in a horizontal plane. The pitman 166 has formed therein a slot 169. A block 170 is secured to the under face of the pitman 166 near its outer end. A lever 171 is carried by a pivot 172 in a support 173 carried by the table 75. The lever 171 engages against the block 170 to raise the pitman 166 as described below.

A vertical lever 174 is carried on the pivot 172 and formed with a reduced upper end 175 which is adapted to enter the slot 169 in the pitman 166. The lower end 176 of the lever 174 is reduced and disposed in an opening 177 in the rockable plate 81. Connected to the lever 174

is a spring 178 having its opposite end connected to a post 179 carried by the table 75.

The pitman 166 will reciprocate with the rotation of the disc 152 and the movement of the pitman 146. The upper end 175 of the lever 174 will be engaged at the extremity of the slot 169 and will be moved to the right to the position shown in Figure 9. The lower end 176 of the lever 174 will be moved to the left and will move the plate 81 which in turn will move the levers 88 and 89 to the position shown in Figure 2. This action of the levers 88 and 89 will feed a frame 56 onto the trackway 143.

Since the pitman 166 moves a greater distance than the distance the lever 174 moves, the short lever 171 raises the pitman 166 to the dotted line position shown in Figure 9. As the pitman 166 is moved upward the end 175 of the lever 174 is released from the slot 169 and the spring 178 returns the lever 174 to its normal position. This return motion reverses the action of the plate 81 and the parts controlled by it. The levers 88 and 89 are then retracted to a point beyond the curved edges 78 of the table 75 so as to be out of the path of movement of frames 56 being delivered by the gate 86. On the return stroke of the pitman 166 the slot 169 will be above the end of the lever 174 and as the short lever 171 moves downward the end 175 of the lever 174 will again enter the slot 169. The lever 171 will come to rest on the support 173 in the full line position of Figure 9. The pitman 166 and the block 170 will continue to the left to the full end of the stroke, the pitman 166 sliding on the upper end of the lever 171.

After a frame 56 has passed through the various tanks 110 and 111, it will be ejected from the trackway 143 by the action of the members 164 and will be deposited in the delivery chute 180. The delivery chute 180 is supported by the right-hand posts 117 and 118 and communicates with an opening 181 in the booth 12 through which the frames 56 are deposited in a receptacle 182 on the outside of the booth. The lower end of the delivery chute 180 may be connected to the booth 12, but preferably is carried entirely by the posts 117 and 118. The opening 181 is provided with a covering 183 which may be made of fabric or other materials to exclude light from the interior of the booth 12.

The speed with which the film 20 is developed depends to a great extent on the temperature of the chemicals in the tanks 110 and the temperature of the wash water in the tanks 111. Carried by the booth 12 is a gauge 184 connected to a thermometer in the developing tanks so as to show the temperature. Where it is desired to change the speed of the developing the speed of the motor 120 is varied by a resistance 185 located on the booth 12.

A curtain 186 is also provided on the booth 12 so that proper lighting may be obtained for the subject to be photographed through the medium of the lights 14 without any outside light being permitted to enter. The booth 12 is also provided with a door (not shown) so that an operator may enter the booth 12. Preferably the door is formed with a curtain adjacent thereto so that an operator may enter the booth 12 without admitting outside light.

Cycle of normal operation

70

When it is desired to make one or more pictures the camera 13 is loaded with a roll of film 20 which is led from the film roll 19 between the feed rolls 21 and under the reflecting prism 17. 75

The subject is seated on the stool 16 so as to be in proper alignment with the lens of the camera 13, the lights 14 are lit and the curtain 186 is drawn. The handle 22 is operated to move the links 24 and rock the plate 25 which causes the member 27 to press against the shutter release 18 and make an exposure.

As the plate 25 rocks, the pawl 33 moves along the ratchet 32 and when the parts are returned to their normal position the ratchet 32 is moved, which turns the feed roll 21 and moves the exposed portion of the film 20 through the slot 53 and presents an unexposed portion of film under the reflecting prism 17. During the course of this operation the pawl 36 has engaged the ratchet 37 and moved the same one step.

As the exposed film 20 moves through the slot 13 it is received in the channel member 60 of the lowermost frame 56 in the rack 62. The exposure operation is repeated as often as desired. In the construction shown four exposures are made at which time one pin 38 on the ratchet 37 moves past the end of the lever 40 thereby releasing the lever 40 and causing the clapper 42 to strike the bell 43 to indicate that four exposures have been made.

The handle 44 is then operated which moves the links 46 and 47 and the plate 48 on its pivot 49. The initial motion of the plate 48 causes a cam action on the extension 52 of the knife 50 to cause the knife 50 to cut the film. At this time the plate 48 is in the position shown in Figure 3, the pin 66 having moved from the left to the right-hand end of the slot 65. Further movement of the plate 48 moves the link 64 to the right-hand of Figure 3 and the link 64 moves the bellcrank lever 67, which forces the ejector plate 73 to push the loaded frame 56 out of the rack 62. As the frame 56 is ejected from the rack 62, the ends of the transverse member 57 engage the extension 76 on the table 75 and the frame 56 falls to a vertical position, supported by the table 75 in the open space between the curved walls 78. As the loaded frame 56 is ejected the next empty frame 56 falls into position to be loaded with a section of exposed film 20.

Since the frame 56 has been ejected the exposure operation may be repeated and two or more frames 56 may be accumulated on the table 75 before being delivered to the developer. As each frame 56 is delivered to the table 75 it will pass under the swinging gate 86. If the gate 86 is forward of the frames 56 at the time they are delivered to the table 75, the gate 86, upon retraction, 55 will rock on the rod 84 and fall behind the frames 56 where it will be held from further motion by the stop pins 87. The handle 79 is operated which transmits motion through the shaft 80 and gears 81 to rotate the post 82, which controls the gate 86. The gate 86 will move in an arc sliding the frames 56 along the table 75 to a point adjacent the developer in alignment with the shaft 80. The gate 86 will be returned to normal position either by appropriate spring action or by manual operation of the handle 79.

As the disc 152 rotates on the shaft 125 the horizontal pitman 156 will move the lever 174 to move the plate 91 which will move both levers 88 and 99 to engage one or more frames 56 to deliver the same to the trackway 143. If desired, the levers 88 and 99 may be forked at their forward ends so as to provide contact both behind and in advance of the frames 56 to more readily control the travel of the frames 56. When the levers 88 and 99 operate on the frames 56 the levers

will be in the position shown in Figure 2. As the levers 88 and 99 move, the latch 102 (Figure 10) will move into the detent 101 in the post 82 and prevent movement of the gate 86. As the lever 99 returns to its normal position the pin 104 on the lever 99 will ride against the latch 102 to remove the latch from the detent 101, thereby freeing the post 82 and the gate 86.

When the levers 88 and 99 are operated to deliver the frames 56 to the trackway 143, the trackway 143 is in the lowered position shown in Figures 1 and 7 and a portion of the cam 126 on either side of the point 128 (Figure 7) is in contact with the lever 131. As the cam 126 continues to turn, the cam face 127 will contact and depress the lever 131 causing the link 133 to move downward, which causes the longitudinal frame 137 to rock downward on the bar 136, which raises the frames 140 and the trackway 143 to the position shown in Figure 8.

While the cam face 127 is in contact with the lever 131 the trackway 143 will remain raised and during this period the stud 153 will be in the upper part of the slot 151 of the vertical pitman 146 and will move the pitman from right to left thereby rocking the lever 159 on its pivot 160. The action of the lever 159 will move the bar 158 to the right carrying with it the angle members 164. Since the frames 56 and the trackway 143 in the raised position are in the path of movement of the angle members, the initial angle member 165 will contact the frame 56 and move it along the trackway 143 to a position above the left-hand portion of the first developer tank 110.

As the cam face 127 rides past the lever 131, the weight of the trackway 143 with its associated parts will cause it to move downward and the frame 56 with its section of film 20 will be immersed in the first tank 110. The counter-weight 139 is such that the trackway 143 may move downward when the cam face 127 rides past the lever 131. As the cam 126 continues its motion the several projections 128 will successively contact the lever 131 and cause a small upward movement of the trackway 143 and a consequent downward movement as each projection 128 rides past the lever 131. This effects a desired agitation of the frame 56 in the tank 110.

When the cam face 127 again depresses the lever 131 and raises the trackway 143, the second angle member 164 will engage the frame 56 and move it to a point over the right-hand portion of the tank 110 into which it will be immersed again. It will be noted that the tanks 110 are approximately twice as wide as the wash tanks 111 so that each frame 56 will be immersed and held in each tank 110 twice as against once in the wash water of the tanks 111. Of course, if desired, the tanks 110 and 111 may be differently arranged, so that on each movement of the frame 56 in the trackway 143, the film will be immersed in a different tank.

On the next cycle of the cam face 127 the frame 56 will be moved to the succeeding tank 111. As the frame 56 is raised for movement from one tank to another any surplus fluid will drain through the openings 61 in the frame 56 and return to the tank of its origin. Since the wash waters in tanks 111 are constantly flowing, there is no possibility of small quantities of chemicals from one tank 110 being carried into another developing tank 110. The operation is continued automatically until the frame 56 has passed through all of the tanks 110 and 111, the final tank being a wash water tank 111. In the mean-

time, additional frames 56 will have been delivered to the trackway 143 while it is in the lowered position and be advanced on the trackway 143 when it is in the raised position.

5 As the frame 56 is raised from the last tank 111, the film 20 is fully developed. Where direct positive paper is used the picture is completed. The right-hand end of the trackway 143 is open as is the left-hand end and the last angle member 164 pushes the frame 56 out of the trackway 143 into the delivery chute 180, whence it may be removed to the receptacle 182. The developed film 20 is removed from the frame 56 and the frame 56 is ready to be again placed in the rack 15 62. When it is desired to adjust the speed of operation because of the temperature of the developing chemicals, the resistance 185 is used to control the speed of the motor 120 which controls the timing of all of the operations. With 20 this arrangement a single operator is sufficient to produce finished pictures as rapidly as the subjects can be posed and the exposures made.

Emergency operation

25 In the event of a breakdown an operator may enter the booth 12 and operate from the inside all of the mechanism or any portion thereof. In the event the camera mechanism falls out of order it is a simple matter to operate the shutter release 18 by hand and to move the ratchet 32 to feed the film 20. In like manner the knife 50 may be operated by hand if desired. From that point onward the mechanical ejector may be used and the automatic developer will continue the rest of the steps.

In the event the difficulty arises in the ejector mechanism the operator may readily remove the lowermost loaded frame 56 from the rack 62 by hand and place the frame 56 on the table 75 40 at a point in front of the levers 88 and 99 so that the levers will feed the frame 56 to the trackway 143 at the proper time.

In the event of a breakdown in the operation 45 of the levers 88 and 99 the pivot 167 may be easily removed from the horizontal pitman 166 and the pitman removed so that the levers 88 and 99 do not operate and the frame or frames 56 may be inserted in the trackway 143 by hand.

In the event of a breakdown of the developer 50 mechanism the wing nuts 118 may be readily removed. The frame 118 and all of the developer mechanism carried thereby may be readily lifted from the tank 106 and placed somewhere else. It will be noted that the pitman 166 is not connected to either of the levers 171 or 174 so that 55 an easy removal of all the parts is possible. The operator may then receive the frames 56 directly from the rack 62 or from the table 75 if the gate 86 and its associated parts are in operation. The operator may then immerse the frames 56 with the film 20 in the various tanks 110 and 111 and develop the film 20 by hand in the well known manner of hand development. When the film 20 is finally developed it may be delivered by hand 60 through the chute 180, and the operation is then completed.

Having thus fully described the invention, what is claimed as new and desired to be secured by Letters Patent, is:

70 1. Apparatus for producing pictures comprising, in combination, a camera including means to expose and advance a film, a frame to receive a section of exposed film from the camera, means to place the frame on a developer and a developer comprising developing tanks and a

trackway disposed in movable relation to each other and means to move the frame on the trackway through successive stages of development.

2. Apparatus for producing pictures comprising, in combination, a camera including means to expose and advance a film, a frame to receive a section of exposed film from the camera, means to place the frame on a developer and a developer comprising developing tanks, a movable trackway adjacent the tanks, means to move the trackway and means to advance the frame on the trackway.

3. Apparatus for producing pictures comprising, in combination, a camera including means to expose and advance a film, a frame to receive a section of exposed film from the camera, means to place the frame on a developer and a developer comprising developing tanks, a movable trackway adjacent the tanks, means to move the trackway and means to advance the frame on the trackway, the action of the last two mentioned means being synchronized.

4. In an apparatus for producing pictures including a camera and a developer, a film holder to receive a section of exposed film, a means to deliver a film holder from the camera to the developer comprising a support for a film holder, a rotatable post, means operated by the post to engage and move a film holder on the support, means to rotate the post and a pair of levers to move a film holder onto the developer.

5. In an apparatus for producing pictures including a camera and a developer, a film holder to receive a section of exposed film, a means to deliver a film holder from the camera to the developer comprising a support for a film holder, a rotatable post, means operated by the post to engage and move a film holder on the support, means to rotate the post, a pair of levers to move a film holder onto the developer and means to lock the post against movement when the levers are being operated.

6. Apparatus for producing pictures, comprising, in combination, a camera including means to expose and advance a film, a frame to receive a section of exposed film from the camera, mechanical means to transfer the frame to a developer, auxiliary automatic means to feed the frame onto the mechanism of the developer, automatic mechanism to carry the frame through successive stages of the development of the film, a motor, a disc operated by the motor and levers operated by the disc to move the frame feeding means and to advance the frame on the developer, said levers being pivoted to the disc by easily removable bolts so that they may be readily disconnected therefrom.

7. Apparatus for producing pictures comprising, in combination, a camera including means to expose and advance a film, a frame to receive a section of exposed film from the camera, mechanical means to transfer the frame to a developer, auxiliary automatic means to feed the frame onto the mechanism of the developer, automatic mechanism to carry the frame through successive stages of the development of the film, a motor, a disc operated by the motor and levers operated by the disc to move the frame feeding means and to advance the frame on the developer, said levers being pivoted to the disc by easily removable bolts so that they may be readily disconnected therefrom to permit manual operation of the automatic means or mechanism in the event of breakdown in the apparatus.

8. Apparatus for producing pictures comprising

- 5 ing, in combination, a camera, including means to expose and advance a film, a frame to receive a section of exposed film from the camera, said frame being one of a stack of frames in horizontal position, means to eject the frame from the stack, a support to receive the frame in a vertical position when the frame is ejected, a rockable member to move the frame from adjacent the stack to adjacent a developer and a developer to develop the film in the frame.
- 10 9. In an apparatus for producing pictures including a camera and a developer, means to support a section of exposed film, a movable trackway to receive the film supporting means in association with the developer, and means to move the film support onto the trackway comprising a pair of levers operating synchronously with the movable trackway, said levers and trackway being operated from a single disc through the medium of a plurality of levers operated by said disc.
- 15 10. In an apparatus for producing pictures including a camera and a developer, means to support a section of exposed film, a movable trackway to receive the film supporting means in association with the developer, and means to move the film support onto the trackway comprising a pair of levers normally out of the path of movement of the film support and operable to engage the film support to move the same onto the trackway and means to move the levers.

11. In an apparatus for producing pictures including a camera and a developer, means to support a section of the exposed film, a movable trackway to receive the film supporting means in association with the developer, and means to move the film support onto the trackway comprising a pair of levers normally out of the path of movement of the film support and operable to engage the film support to move the same onto the trackway in a predetermined time relationship to the movement of the trackway and means to move the levers.

12. Apparatus for producing pictures comprising, in combination, a camera including means to expose and advance a film, a frame to receive a section of exposed film from the camera, a developer to receive the frame and film, said developer comprising developing tanks and a trackway disposed in movable relation to each other and means to move the frame on the trackway through successive stages of development.

13. Apparatus for producing pictures comprising, in combination, a camera including means to expose and advance a film, a frame to receive a section of exposed film from the camera, means to develop the film, and a developer comprising tanks, a movable trackway adjacent the tanks, means to move the trackway and means to advance the frame on the trackway.

30 G. PETER GRANT, Jr.
